* cited by examiner

Primary Examiner — Cathron C Brooks*Assistant Examiner* — Ian F Whitmore(74) *Attorney, Agent, or Firm* — Renner, Otto, Boisselle and Sklar, LLP(57) **CLAIM**

The ornamental design for a display screen with graphical user interface, as shown and described.

DESCRIPTION

The sole FIGURE is a front elevation view of a display screen with graphical user interface showing our new design.

The outermost broken-line perimeter illustrates a display screen and forms no part of the claimed design. The remaining broken lines illustrate portions of a graphical user interface and form no part of the claimed design.
